UNITED STATES PATENT OFFICE.

WALTER KIESER, OF CHARLOTTENBURG, GERMANY, ASSIGNOR TO GENERAL ELECTRIC COMPANY, A CORPORATION OF NEW YORK.

AUTOMATIC STARTING DEVICE FOR BOILER FEED-PUMPS.

1,170,163.

Specification of Letters Patent.

Patented Feb. 1, 1916.

Application filed June 19, 1914. Serial No. 846,146.

To all whom it may concern:

Be it known that I, WALTER KIESER, a citizen of the Swiss Republic, residing at Charlottenburg, Germany, have invented 5 certain new and useful Improvements in Automatic Starting Devices for Boiler Feed-Pumps, of which the following is a specification.

This invention relates to mechanism for 10 feeding water to steam boilers.

It is well known that it is an advantage 15 to furnish to such boilers water that is as hot as possible, and many feed water heaters are in use. It is always difficult, however, to feed hot water by means of pumps, owing 20 to the impairment of the suction capacity of the pumps, due to the readiness with which the hot water gives off vapor and thus reduces the vacuum produced by the pump. This fact is especially troublesome in the 25 case of centrifugal pumps, and renders it difficult to start such machines.

The object of the present invention is to 30 overcome the difficulties inherent in starting a centrifugal feed pump and at the same time provide for heating the feed water.

It comprises briefly an improved arrangement 35 wherein the exhaust steam from the engine which drives the pump is discharged through a suitable nozzle into that portion of the suction pipe which dips into the water tank, the jet of steam being in the direction in which the column of water flows through said pipe to the pump. The steam imparts velocity to the water and at 40 the same time is condensed and imparts its heat to the water, so that the device serves not only as a starting means but also as a feed water heater and condenser.

For a consideration of what I believe to 45 be novel and my invention, attention is directed to the accompanying specification and the claims appended thereto.

In the accompanying drawing, Figure 1 50 is a diagrammatic representation of a boiler feed system embodying my invention, and Fig. 2 shows a modification of a portion of the system.

The pump 1 is of the centrifugal type and takes water from the tank 2, delivering it 50 through the pump suction pipe 3 and delivery pipe 4 to a boiler (not shown). The delivery pipe is preferably provided with a check valve 5 to prevent return of the water from the boiler. In the lower part of the 55 suction pipe where it is submerged in the water in the tank, there is a nozzle 6 located preferably in an enlarged portion of the suction pipe which has a tapering throat 7 communicating with the upper portion of 60 said pipe. The nozzle is connected by means of the pipe 8 with the exhaust of the engine 9 which drives the pump. The engine shown is a turbine, direct connected to the pump; but any desired type of engine may 65 be used, connected to the pump in any suitable manner. The nozzle discharges the exhaust steam through the tapering throat 7 into the upper portion of the suction pipe, in the same direction as the column of water 70 flowing through said pipe to the pump.

Before the pump is set in operation, the water stands at the same level both inside and outside the suction pipe. When steam is turned into the engine it exhausts through 75 the nozzle and forces the water above it up through the pipe 3 and at the same time sucks water out of the tank into the lower end of said pipe. The pump is thus relieved 80 of the work of raising the water and starts promptly to deliver it to the boiler. During the operation, the exhaust steam is condensed by the inflowing feed water, so that 85 said water is raised in temperature by the heat it absorbs from the steam. This operates to relieve the engine to a certain extent of the back pressure of the exhaust. The continuous discharge of the steam into the suction pipe prevents the column of 90 water in the suction pipe from breaking, in case the speed of the pump fluctuates.

The effect of the steam at the start is necessarily greater in proportion to the height of the column of water above the nozzle, and in order to derive as much advantage along this line as possible, the noz-

zle may be placed at the lower end of the suction pipe. Fig. 2 shows one way of doing this; the nozzle being placed in a chamber formed by the casting 10, which has inlet 5 ports 11 in its bottom, and is provided with a converging throat at its upper end to coöperate with the nozzle in effecting the ejector action of the steam upon the water. This construction lends itself to the employment 10 of a check valve to prevent the return to the tank of the water in the suction pipe when the pump ceases to operate. The valve may be an annular member 12 surrounding the nozzle and sliding vertically thereon; opening upwardly to admit the water, and shutting by gravity when the flow stops. In Fig. 1, the check valve is shown preferably as a flap valve 13 controlling the inlet 15 to the casting 14 in which the nozzle is preferably housed.

In case the pressure in the suction pipe becomes unduly great, owing to a sudden drop in the load or other cause, which causes a rush of steam into said pipe, the excess of 20 pressure can be relieved by means of a safety valve 15 in the exhaust pipe, through which the extra steam will be blown off. Or, in order to avoid the waste of heat arising from blowing off the steam, the excess of 25 pressure in the suction pipe can be relieved by an overflow or relief valve 16 located between the nozzle and the check valve 5, and conducting the hot water back to the tank, or elsewhere. In this way the steam 30 will always be utilized. In case both of these safety devices are used in the same system, the relief valve can be arranged to open first, and the safety valve only when a considerably higher pressure has been 35 reached; thereby saving the heat of the exhaust steam except at peaks of pressure.

It may sometimes happen that the condensing of the steam in the exhaust pipe, when the engine has been stopped, will cause 40 the water in the tank to rise in said pipe and possibly flood the engine. In order to avoid this, a check valve 17 may be installed in the exhaust pipe; or said pipe may be carried upward from the engine in a loop 45 18 which is at such a height above the water in the tank as to prevent the atmospheric pressure thereon from forcing it up to the loop. With this arrangement the pump, suction pipe and exhaust pipe are always full 50 of water, as soon as the pump is once running. The pump will therefore act as soon as the steam enters the pipe.

In accordance with the provisions of the 55 patent statutes, I have described the principle of operation of my invention, together with the apparatus which I now consider to represent the best embodiment thereof; but I desire to have it understood that the

apparatus shown is only illustrative, and that the invention can be carried out by other means.

What I claim as new and desire to secure by Letters Patent of the United States, is,—

1. The combination with a boiler feed pump, of an automatic starting device comprising a suction pipe for said pump, a tank into which said pipe dips, and a steam ejector arranged in said pipe below the level of the water in said tank.

2. The combination with a boiler feed pump, of an engine for driving the same, and an automatic starting device for said pump comprising a suction pipe, a tank into which said pipe dips, and an ejector arranged in said pipe below the level of the water in said tank and connected with the exhaust pipe of said engine.

3. The combination with a boiler feed pump driven by an engine, of a suction pipe from said pump, and an ejector connected with the exhaust pipe of said engine and arranged at the lower end of said suction pipe.

4. The combination with a boiler feed pump driven by an engine and having suction and delivery pipes, of a tank into which the suction pipe dips, an ejector in said suction pipe located below the level of the water in the tank and connected with the exhaust of said engine, and check valves in said suction and delivery pipes.

5. The combination with a boiler feed pump driven by an engine and having suction and delivery pipes, of an ejector in the suction pipe connected with the exhaust pipe of said engine, a check valve in the suction pipe, and means for relieving any excess of pressure in said suction pipe.

6. The combination with a boiler feed pump driven by an engine and having suction and delivery pipes, of an ejector in the suction pipe connected with the exhaust pipe of said engine, a check valve in the suction pipe, and means for relieving any excess of pressure in said suction pipe comprising an overflow valve in the suction pipe.

7. The combination with a boiler feed pump driven by an engine and having suction and delivery pipes, of an ejector in the suction pipe connected with the exhaust pipe of said engine, a check valve in the suction pipe, and means for relieving any excess of pressure in said suction pipe comprising an overflow valve in the suction pipe, and a safety valve in the exhaust pipe.

8. The combination with a boiler feed pump driven by an engine and having suction and delivery pipes, of an ejector in the suction pipe connected with the exhaust pipe of said engine, a check valve in the suction pipe, and means for relieving any excess of pressure in said suction pipe comprising

an overflow valve in the suction pipe, and a safety valve in the exhaust pipe, said relieving valves being arranged to open in succession.

5 9. The combination with a boiler feed pump driven by an engine, of suction and delivery pipes for said pump, an ejector in the suction pipe, and an exhaust pipe for said engine connected with said ejector and

provided with a loop rising to a barometric height above the level of the water supply.

In witness whereof, I have hereunto set my hand this fourth day of June, 1914.

WALTER KIESER.
